SANITARY NAPKIN MACHINE

Courtney P. Winter, Chambersburg, Pa., assignor
to Frens Corporation, Chambersburg, Pa., a
corporation of Pennsylvania

Application May 4, 1929, Serial No. 360,595

15 Claims. (Cl. 223—15)

This invention relates to new and useful improvements in machines for the manufacture of sanitary napkins and the primary object resides in the provision of a machine of this character which will produce a continuous web of material properly folded and enclosing therein at regular intervals pads formed of a specific absorbent material, shaped for proper application to the body of the wearer, the web enclosing said pads being adapted for cutting into individual sanitary napkins ready for use.

A further object of the invention resides in providing an improved means for automatically placing upon a continuous web a quantity of wood wool, adapted to be shaped to form the pads for the napkins.

Still another object of the invention resides in the provision of an improved shaping means, whereby said pads of wood wool are tapered at their edges to effect a proper fitting to the body when in use.

A further object of the invention resides in an improved means for folding the web of material over the pads deposited thereon to properly enclose the same.

Still another object resides in the provision of an improved means for depositing on the web of material, prior to the deposit of the pad material thereon a layer or film of cotton fiber, so that when the pad is enclosed within the web of material, said pad will be also enveloped in the cotton fiber film to prevent the sifting of the pad material through the covering of the napkin.

A still further object resides in providing a machine which is comparatively simple and durable in construction, inexpensive to manufacture and one which will be very efficient and useful in operation.

With these and numerous other objects in view, my invention consists in the novel features of construction, combination and arrangement of parts as will be hereinafter referred to and more particularly pointed out in the specification and claims.

In the accompanying drawings forming a part of this application:

Figure 1 is a side elevation, with parts in section, of a machine constructed in accordance with my invention;

Figure 2 is a similar view of a continuation of the machine illustrated in Figure 1;

Figure 3 is a plan view of the device shown in Figure 1 of the drawings;

Figure 4 is a plan view of a part of the machine shown in Figure 2;

Figure 5 is a plan view of that part of the machine forming a continuation of the device as shown in Figure 2;

Figure 6 is an enlarged vertical section as seen on the line 6—6 of Figure 4;

Figure 7 is an enlarged vertical section as seen on the line 7—7 of Figure 5, with a knife in its raised position;

Figure 8 is an enlarged transverse section as seen on the line 8—8 of Figure 4;

Figure 9 is a similar view as seen on the line 9—9 of Figure 4;

Figure 10 is a similar view as seen on the line 10—10 of Figure 4;

Figure 11 is a similar view as seen on the line 11—11 of Figure 4;

Figure 12 is a transverse section as seen on the line 12—12 of Figure 5, showing the knife blade in elevation;

Figure 13 is a vertical longitudinal section through one of the rotating elements for depositing material on the web forming the covering or wrapping for the napkin;

Figure 14 is a vertical transverse section through the elements shown in Figure 13;

Figure 15 is a vertical transverse section as seen on the line 15—15 of Figure 1;

Figure 16 is a plan view of a fragment of one of the rotary elements showing the shape of the opening therein through which the material is blown onto the continuous web;

Figure 17 is a side elevation, partly in section, of a slight modification of the rotary element used in the machine;

Figure 18 is a transverse section therethrough as seen on the line 18—18 of Figure 17;

Figure 19 is a fragmentary plan view of a web forming the covering of the napkin having a film of cotton fiber deposited thereon, and

Figure 20 is a similar view after the deposit of the wood wool on the film of cotton fiber.

In describing the invention I shall refer to the drawings in which similar reference characters designate corresponding parts throughout the several views and in which 1 designates an elongated frame upon which are supported in spaced relation to one another the rotating cylindrical members 2 and 3, respectively. These members are rotatable from the axes 4 and 5, respectively and each has its periphery provided with a plurality of spaced openings 6 which are shaped as illustrated in Figure 16 of the draw-

ings. These openings are spaced at regular intervals throughout the periphery of the rotating element and mounted within the elements 2 and 3 and communicating with the openings 6 5 therein are the tubular conduits 7. These conduits taper toward their inner ends and the inner ends are angularly bent as shown at 8 to connect with openings 9 formed in one side wall of the rotating element.

10 A pair of blowers 10 and 11 are provided respectively with the conduits 12 and 13 which respectively operate in connection with the openings 9 of the respective rotating elements 2 and 3. As shown clearly in Figure 15, the 15 upper end of each of these conduits 12 and 13 is bent angularly and is provided with a bearing 14 which abuts the side wall of the rotating elements. As these rotating elements are in operation, the openings 9 therein register with the 20 ends of the conduits 12 and 13 so that material blown from the blower will enter the tubular passages 7 and pass therefrom through the openings 6, as the machine is operated.

The blower 10, through the medium of a pipe 25 15 communicates with a source of supply whereby cotton fibers are fed to and through the rotating elements 2 while a conduit 16 connects with the blower 11 and communicates with a source of supply of finely disintegrated wood 30 pulp known to the art as wood wool.

Mounted above the rotary member 2 in spaced relation to one another and in slightly spaced relation to the member 2 are the rollers 17 and 18 and similar rollers 19 and 20 are mounted 35 above the rotating element 3. Mounted below the rotating element 2 and forward thereof is an additional roller 21 while a similar roller 22 is rotatably mounted below the rotating element 3 and rearward thereof. An endless belt 23, formed of fabric or any other desired material extends over these rollers and partially over the rotating elements 2 and 3, as clearly shown in the somewhat diagrammatic view illustrated in Figure 1. Rotatably mounted at the forward end of the frame 40 1 is a roll of gauze designated by the numeral 24. This gauze is passed over the belt 23 as it passes over the rollers 17 and 18 and under the belt in contact directly with the peripheral face 45 of the roller 2 as said belt passes over the latter, then over the belt as it passes over rollers 19 and 20 and under said belt as it passes over the rotating member 3. The web of gauze is then continued on through the machine in a 50 manner to be hereinafter and more particularly described.

As this gauze 24 passes over the rotating member 2, a thin film or layer of disintegrated cotton fibers are deposited thereon at regular intervals, which fibers are directed through the member 2 from the blower 10 and in Figure 19 there is disclosed a plan view illustrating the film or layer of cotton fibers on the gauze designated by the numeral 25. The gauze strip or web continuing from the member 2 by action of the belt 23 brings its patches or layers of cotton fibers in contact with the peripheral face of the member 3 and the latter is timed with respect thereto so that there will be deposited 60 on each film or layer of cotton fiber a wad of wood wool blown thereon through the medium of the blower 11. In Figure 20 I have illustrated this wad or pad of wood wool and designated the same by the numeral 26, the same being shown deposited upon the film or layer of

cotton fiber 25 which in turn is carried on the gauze strip 24.

Any source of power (not shown) may be provided for the rotation of the elements 2 and 3, it being understood that as one element is rotated and the endless belt 23 is carried thereover, the other will be simultaneously rotated which in turn will carry the gauze 24 thereover.

As the web of gauze leaves the endless belt 23 it is conveyed onto an endless carrier 27, the upper stretch of which forms substantially a table therefor. This endless carrier 27 is operated by means of a chain 28 extending over sprockets 29, 30 and 31 operating on shafts 32, 33 and 34, respectively. These sprockets are supported on the frame in a manner more particularly and clearly set forth in Figures 2 and 6 of the drawings. As the wads or pads of wood wool on the web of gauze are carried on this endless carrier 27 they are adapted to be shaped into a form well adapted to fit the body of the wearer. These wads or pads 26 are first brought into contact with a pair of diagonally disposed rotary discs 35, the peripheral edges of which engage the side portions of the pads 26 and taper the side edges of said pads or wads of wood wool, so that the same will be higher or thicker in the center than at the side edges. These shaping discs 35 are carried on arms 36 which are suspended from a transverse shaft 37 carried on the support 38. Also mounted on the shaft 37 is a central flattening roller 39 which contacts with the pads 26 after they are shaped by the discs 35. This roller 39 flattens out the wood wool, so that the particles thereof adhere closely one to the other and the height which has been exaggerated by reason of the shaping discs 35 will be reduced.

Arms 40 project rearwardly from the supports 38 and have pivoted therebetween a pressing plate 41 which is elongated in design and tends to contact with the upper face of the pads 26 as they progress over the endless carrier 27 to keep said pads in proper shape during the folding of the web 24 thereover.

As the web or strip of gauze 24 with the pads 26 thereon moves along the conveyor 27, said web or strip of material is intended to be folded transversely and envelope or enclose said pads. To this end I provide an endless belt 42 which is arranged to operate on a horizontal plane just slightly above the plane of the upper stretch of the conveyor 27, best shown in Figures 2, 3 and 6 of the drawings. This belt 42 extends over pulleys 43 and 44 on one side of the machine and over pulley 45 operating on the opposite side of the machine, well shown in Figure 4 of the drawings. These pulleys are respectively mounted on vertical shafts 46, 47 and 48. The shaft 48 is a driven shaft which causes the belt 42 to be actuated when said shaft is rotated. The stretch of the belt 42 between rollers 45 and 43 first contacts with one side of the web 24 and tends to turn it inwardly as shown in Figure 4 and this inwardly folded portion of the web 140 is held downwardly in place over the base or central portion of the web by means of a downwardly pressing elongated plate 49, as clearly shown in Figure 4 of the drawings. The stretch of the belt 42 between the pulleys 44 and 45 145 contacts with the opposite side edge of the web 24 and tends to fold it inwardly over the folded portion of the web, as shown in Figure 4 so that the web becomes folded from each side edge thereof in overlapping relation to enclose therein 150

the pads or wads 26 of wood wool. If desired, some means may be provided (not shown) to assist in this folding operation, although it has been found that the belt 42 will accomplish 5 the desired results. The downwardly pressing plate or strip 49 is pivotally supported on a shaft 50 extending transversely of the carrier 27 and supported in the arms 51, as clearly shown in Figure 4 of the drawings. It may be here 10 stated that in starting the machine the web is folded over in position by hand and drawn under the folding members to start the folding operation.

As stated above, the pulley 45 is carried on a 15 vertical shaft 48, shown clearly in Figures 2 and 6 of the drawings and this shaft 48 carries intermediate its ends an additional pulley 52 over which extends a belt 53 trained over a pulley 54 carried on a longitudinal shaft 55. On 20 this shaft 55 is a pinion 56 meshing with a pinion 57 carried on the shaft 33. A motor 58 drives the shaft 34 through the medium of a belt 59 and a pulley 60 and as this shaft 34 connects with the shaft 33 through the medium 25 of the endless belt and chain 27 and 28, it will be seen that the shaft 55 will be rotated upon the rotation of the shaft 34 to actuate the elements and parts connected therewith.

This shaft 55 extends rearwardly of the 30 section of the machine carrying the belt 27 and has a knife blade 61 connected with the end thereof which is caused to rotate in a plane transversely of the machine, as clearly shown in Figures 2, 7 and 12 of the drawings.

The frame of the machine continues beyond 35 that portion supporting the belt 27 and supports therein mechanism carrying an endless conveyor 62. This conveyor 62 comprises preferably a series of slats or the like connected to 40 and held together by means of an endless chain 63 at one side edge thereof. This chain extends over sprockets 64, 65 and 66 which are respectively carried on rollers or the like supported on shafts 67, 68 and 69, respectively. The shafts 45 67 and 68 are supported by the upstanding brackets or supports 70 and the shaft 69 which is suspended from the frame is held in place by means of the bracket 71, clearly shown in Figure 2 of the drawings. The shaft 55 adjacent its rear end has a pinion 72 thereon meshing with a pinion 73 carried on the shaft 67, clearly 50 shown in Figure 5 of the drawings, so that as said shaft 55 is rotated, the shaft 67 will be caused to rotate and correspondingly operate 55 the endless carrier 62.

As the web of folded gauze with the pad enclosed therein leaves the belt 27, the same is fed on to the upper stretch of the endless belt or conveyor 62 and said belt or conveyor is 60 slotted at regular intervals throughout its length, as shown at 74. These slots are provided by the omission of a slat at regular intervals and these slots provide for the passing of the knife blade 61 therethrough as the shaft 55 is rotated, it 65 being understood of course that the belt or conveyor 62 and the shaft 55 are timed so that the knife blades will enter the slots 74 as the knife blade is rotated. Obviously the folded web of gauze with the pads therein will be cut as the 70 knife blade passes therethrough and the individual napkins will thus be formed, as clearly illustrated in Figure 5 of the drawings. These individual napkins are designated in the drawings by the numeral 75. As these napkins are 75 cut and fed from the endless carrier or con-

veyor 62, the same are collected, the ends of the web of gauze folded over the pad portion thereof and the same boxed and made ready for shipment.

In Figures 17 and 18 I have shown a slightly 80 modified form of the invention which is adapted for use in connection with a specific type of napkin and whereby one of the two rotary elements heretofore described may be eliminated. To this end I provide a rotary element 76 similar to the rotary elements 2 and 3, heretofore described, except that the same is provided with a greater number of openings in the periphery thereof and correspondingly a greater number of channels or chutes through which material may be blown. 85 The openings in the peripheral face of the rotary elements 76 communicate with chutes which I have designated by the numeral 77, all of which terminate in one side wall of the member 76, the openings in the latter wall being designated 90 by the numeral 78. An arcuate plate or the like 78 is supported against the latter wall of the member 76 and supports therein a U-shaped manifold or the like 79 which communicates with a conduit 80. The two openings of the 95 manifold 79 are adapted to register with two openings 78' and an additional conduit 81 is provided which is adapted to communicate with an opening 78' intermediate the two openings which communicate with the arms of the manifold 79. Material, such as cotton fibers, are adapted to be blown through the conduit 80 and through the manifold 79 into the openings 78' connected therewith while other material, such as wood wool or other absorbent material, 100 if desired, is adapted to be blown through the conduit 81. Thus, as the rotary element 76 is caused to rotate under the action of a belt or endless carrier 82 which is adapted to carry a gauze strip 83 thereon, the openings in the 105 member 76 will register successively with the arms of the manifold 79 and the conduit 81. The upper arm of the manifold 79 will deposit on the web of gauze a film or layer of cotton fiber, for instance, and as that same opening 110 next registers with the opening in the conduit 81, material, such as wood wool, will be deposited on the cotton fiber film or layer and next as said opening registers with the opening in the lower arm of the manifold 79, a second layer or 115 film of cotton fiber will be deposited over the wad or batch of wood or the like which may be deposited on this first film of cotton fiber. In this manner, it will be seen that there may be produced, through the medium of a single rotary element a sanitary napkin, the pad of which 120 may consist of alternating layers of cotton fiber and wood wool or other absorbent material which may be used. By this means the duplicating of rotary elements is eliminated and it 125 will further be seen that when wood wool is used as the intermediate layer which may be fed to this rotary element such material will be entirely enveloped or enclosed within layers of cotton fiber to prevent said wool from sifting 130 through the gauze covering of the napkin when completed. On the other hand, it will be seen that the disposition of material through these conduits to the rotary elements may be reversed 135 from that hereabove described. In other words, wood wool may be utilized for distribution through the conduit 80 and its manifold 79 and cotton fiber distributed through the conduit 81 so that upon the first deposit of material on 140 the web 83, there will be wood wool, on the 145 web 83, there will be wood wool, on the 150

second deposit there will be a layer or film of cotton fiber and a third deposit of wood wool. Thus when the pad is completed it will consist of wood wool through the middle of which will 5 appear a thin layer of cotton fiber, which layer of fiber tends to hold together and strengthen the pad of wood wool.

From the foregoing description of the construction of my improved machine, the operation 10 thereof and the manner of applying the same to use will be readily understood and it will be seen that I have provided a comparatively simple, inexpensive and efficient means for carrying out the objects of the invention.

15 While I have particularly described the elements best adapted to perform the functions set forth, it is obvious that various changes in form, proportion and in the minor details of construction may be resorted to without departing from the spirit or sacrificing any of the principles of the invention.

Having described my invention what I claim is:

1. In a machine for making sanitary napkins, 25 a frame, means for conveying a web over the frame, means for depositing a material on said web at regular spaced intervals, additional means for depositing a separate absorbent material on the first mentioned material on said web, and means for folding said web over the absorbent material thereon.

2. In a machine for making sanitary napkins, 35 a frame, means for conveying a web over the frame, means for depositing a layer of facing material on said web, additional means for depositing on the layer of facing material an absorbent material, means for simultaneously folding the web and layer of facing material about the absorbent material while the layer of facing 40 material is superimposed on said web, and means for cutting said folded web with material therein.

3. In a machine for making sanitary napkins, 45 a frame, means for conveying a web over the frame, rotary means in contact with said web for depositing a layer of cotton fiber on said web at regular spaced intervals thereon, additional rotary means in contact with said web for depositing on the layers of cotton fibers pads of 50 absorbent material and means for folding the web over the material thereon.

4. In a machine for making sanitary napkins, 55 a frame, means for conveying a web over the frame, rotary means in contact with said web for depositing a layer of cotton fiber on said web at regular spaced intervals thereon, additional rotary means in contact with said web for depositing on the layers of cotton fibers pads of 60 absorbent material and means for transversely severing the web at regular intervals to produce individual napkins.

5. In a machine for making sanitary napkins, 65 a frame, means for conveying a web over the frame, means for depositing wads of absorbent material in a free fibrous state on said web, means for compressing said absorbent material into pads of predetermined design, and means for folding said web over the pads of absorbent material.

70 6. In a machine for making sanitary napkins, a frame, means for conveying a web over said frame, means for depositing pads of absorbent material at regular spaced intervals on said web, means for compressing said pads to predetermined shape as the same are fed on the

web over the frame, means for folding the web over said pads to enclose the latter therein and means for cutting the folded web with the pads therein at regular intervals.

7. In a machine for making sanitary napkins, 80 a frame, means for conveying a web over said frame, means for depositing a layer of material at regular intervals on said web, means for depositing a pad of absorbent material on each layer of material on said web, means for compressing said pads to a predetermined shape, and means for folding the web to enclose the pads therein.

8. In a machine for making sanitary napkins, 90 a frame, means for conveying a web over said frame, means for depositing a layer of material at regular intervals on said web, means for depositing a pad of absorbent material on each layer of material on said web, means for compressing said pads to a predetermined shape, and means for folding the web to enclose the pads therein and means for transversely cutting the folded web with the pads therein at regular 95 intervals.

9. In a machine of the character described, 100 an endless carrier to serve as a conveyor for a strip of web, and a rotary member positioned to contact with the web and be partially surrounded by said web and carrier and serving to deposit on said web on regular spaced intervals a specified material.

10. In a machine of the character described, 110 an endless carrier to serve as a conveyor for a strip of web, a rotary cylindrical member positioned to contact with said web and be partially surrounded by said web and carrier, said rotary member having chutes extending therethrough and terminating in the periphery thereof, and means for projecting material under pressure through said chutes for deposit on said web. 115

11. In a machine of the character described, 120 an endless carrier to serve as a conveyor for a strip of web, a rotary cylindrical member disposed to contact with said web and be partially surrounded by said web and endless carrier, 125 said rotary member being provided with radial chutes terminating at one end in the periphery of said member, the opposite ends of said chutes terminating in the side wall of said member, and means in contact with the last mentioned side wall of said member for supplying material to said chute under air pressure for deposit on said web, as and for the purposes described.

12. In a machine of the character described, 130 an endless carrier to serve as a conveyor for a strip of web, a cylindrical distributing member disposed to have its periphery in contact with said web and be partially surrounded by said web and said carrier, said distributing member being provided with distributing channels terminating in the periphery thereof, and means for supplying an absorbent material under air pressure to the channels of said distributing member for deposit on said web. 135

13. The method of producing sanitary napkins 140 consisting in passing a web over a surface, applying to said web at regular intervals thereon an absorbent material in a free fibrous state, compressing the absorbent material to form pads of predetermined shape, folding the web over the 145 absorbent material and cutting the folded web at regular intervals.

14. In a machine for making sanitary napkins, 150 a frame, means for conveying a web over the frame, means for pneumatically depositing ab-

sorbent material in a free fibrous state upon the web at regular spaced intervals, means for folding the web over the absorbent material, and means for cutting the folded web transversely 5 to form individual napkins.

material, applying to said latter material an absorbent material in a free fibrous state, en-folding the absorbent material within both the web and the superimposed facing material of the web, and cutting the folded web at regular intervals.
